UNITED STATES PATENT OFFICE.

JAMES R. LEES, OF DENVER, COLORADO, ASSIGNEE TO THE COLORADO PRESSED STEEL CO., OF DENVER, COLORADO.

COVER FOR BEET-FLUMES.

No. 922,920.

Specification of Letters Patent.

Patented May 25, 1909.

Application filed October 17, 1908. Serial No. 458,322.

To all whom it may concern:

Be it known that I, JAMES R. LEES, a citizen of the United States, and a resident of Denver, in the county of Denver and State 5 of Colorado, have invented a new and Improved Cover for Beet-Flumes, of which the following is a full, clear, and exact description.

This invention relates to flumes such as 10 are used in connection with beet sugar mills for floating beets into the mill from the receiving sheds.

The object of the invention is to produce a flume cover which will be very strong and 15 durable, which can be simply constructed of metal, and which is constructed in such a way as to enable it to be readily removed, and if desired secured in position.

The invention consists in the construction 20 and combination of parts to be more fully described hereinafter and particularly set forth in the claims.

Reference is to be had to the accompanying drawings forming a part of this specification, in which similar characters of reference indicate corresponding parts in all the 25 figures.

Figure 1 is a perspective of a flume cover constructed according to my invention; Fig. 30 2 is a cross section of this cover; and Fig. 3 is a cross section through the flume, and showing the cover applied thereto, the cover being shown in longitudinal section.

Referring more particularly to the parts, 35 1 represents the flume, and 2 represents the cover, which is constructed according to my invention. These covers are applied side by side so as to form a complete cover or deck over the flume. These covers are normally adapted to be raised so as to enable 40 the beets to be thrown down the inclines or chutes 3 into the flume. The cover 2 is formed of light metal, which is adapted to be pressed or molded into the form illustrated. It consists of a rectangular plate, 45 the material whereof is offset downwardly so as to form a plurality of longitudinally disposed ribs 4 on the under side of the plate. The ends of the plate are turned

downwardly so as to form flanges 5, which 50 reduces the bearing surface to a minimum, and these flanges are provided at suitable points with openings 6, by means of which the cover may be fastened, if desired. Near the middle portion of the cover, the ribs 4 55 are spaced equidistant, as shown in Fig. 2, but near the side edges unusually wide spaces or side faces 7 are formed. In these side faces 7, openings or hand-holes 8 are formed, the edges of these openings 8 being pressed 60 downwardly, as shown.

The covers are laid in place transversely of the flume, as indicated in Fig. 3. When it is desired to remove the cover, this may be done by applying a hook at the hand-holes 8.

On account of the reinforcing ribs 4, plates of very thin material may be used for forming the covers, as the ribs reinforce the plate and give it great strength and 70 durability.

The covers will usually be left unattached, but if desired, certain of the covers may be secured by fastening devices applied in any manner through the openings 6 in 75 the flanges 5. Because the cover is supported on the flanges, the surface for the cover is greatly reduced, and this facilitates the removal of the cover in freezing weather. The openings 8 also operate to facilitate the 80 circulation of air through the cover.

Having thus described my invention, I claim as new and desire to secure by Letters Patent,—

1. A flume cover consisting of a metal 85 plate having reinforcing ribs formed therein, and having means for applying a lifting device to raise the cover.

2. A flume cover formed of a metal plate having downwardly projecting flanges on 90 the ends thereof, and having openings in the body of said plate for applying lifting devices.

3. A flume cover consisting of a metal plate having longitudinally disposed reinforcing ribs formed therein, and having 95 flanges formed at the ends thereof.

4. A flume cover consisting of a metal

plate having longitudinally disposed reinforcing ribs formed therein, and having flanges formed at the ends thereof, said cover having hand-holes formed therein to receive lifting devices.

5. A flume cover consisting of a metal plate having longitudinally disposed ribs formed therein, and having flanges at the ends thereof with openings to receive fas-

tening devices, said cover having openings 10 in the body thereof to receive lifting devices.

In testimony whereof I have signed my name to this specification in the presence of two subscribing witnesses.

JAMES R. LEES.
